TWO-DRAWER SHEET DISPENSER

Vincent C. Jones, Appleton, and Archie S. Krueger, Green Bay, Wis., assignors to Marathon Corporation, Menasha, Wis., a corporation of Wisconsin

Application February 2, 1956, Serial No. 40,010

Term of patent 14 years

(Cl. D74—9)

Fig. 1

Figure 1 is a front elevational view of a two-drawer sheet dispenser showing our new design, the rear wall thereof being flat, vertical and unornamented,

Figure 2 is a side elevational view thereof as it appears with the drawers partially pulled out, the side opposite thereto being substantially similar in appearance, and

We claim:

The ornamental design for a two-drawer sheet dispenser, as shown and described.
